UNITED STATES PATENT OFFICE.

WALDO EDWARD BRADEN, OF GIDEA PARK, ENGLAND.

CLOSURE MEANS FOR JARS.

Application filed March 5, 1924. Serial No. 697,100.

To all whom it may concern:

Be it known that I, WALDO EDWARD BRADEN, a subject of the King of Great Britain, residing at Gidea Park, in the county 5 of Essex, England, have invented new and useful Improvements in or Relating to Closure Means for Jars, of which the following is a specification.

This invention relates to closure means for 10 jars and more particularly for glass jars having glass lids provided with washers to ensure an air tight fit. Heretofore the washers have been unattached to either the jar or lid and therefore liable to be separated from 15 the jar upon removal of the lid.

According to the present invention the closure means comprises tongue members and spring clips retained in desired position by a suitable positioning means, the tongues 20 being adapted to retain the washer positively and permanently in position on a seating surface whilst the spring clips are so shaped that upon the fitting of the lid they move outwardly until the lid or jar is 25 brought into contact with the washer when they move to their original position, locking the lid and jar together.

In the accompanying drawing various 30 modifications of my invention are illustrated.

Figure 1 shows one form of my invention having the spring clips and tongues for gripping the washer attached to a metal ring.

Figure 2 is a partial vertical section of 35 Figure 1.

Figure 3 shows a modification wherein wire is substituted for the metal ring.

Figure 4 shows a form of the device for 40 use with jars without a flanged mouth.

Figures 5 and 6 show a further modification in which the spring clips and tongues for gripping the washer are attached to the lid.

45 The lid 1 and jar 2 have inserted between them a washer of cork or the like 3 for ensuring an air tight fit. The washer is attached to the jar by tongues 4 which are united to or made integral with a ring 5 arranged circumferentially around the jar beneath the flanged mouth 6 thereof. The tongues 4 are of such length that they can be bent over the washer to secure it in position but do not extend the entire width 50 thereof, thereby not interfering with the function of the said washer. Spring clip

members 7 are also attached to or made integral with the ring 5 and are so shaped that when fitting on the lid, downward pressure thereof causes the clips to be moved outwardly until the lid is brought into contact with the washer, when they are sprung onto the lid brim to lock the jar and lid together.

As a modification, the ring arranged 60 around the jar can be replaced by wires 8, the spring clips and tongues in such a case being integral. The combined spring clip and tongue members 9 are held in position by the wires 8, one of which is retained against 65 the underside of the flanged mouth 6 of the jar by ridges 11 arranged in the parts of the members 9 held between the jar and the wire. Any other wires 8 used are retained 70 in their respective positions by like means.

When the circumferential ring is of wire, the wire may be shaped to form also the tongues for securing the washer in place and for forming the spring clips, the wire in such an instance being essentially spring 80 wire. Several strands of the wire may be combined to give increased strength.

In the case of jars without flanged mouths, the ring 5 is prevented from rising and allowing the washer to be loosened by 85 an arrangement of retaining bands 12 which pass longitudinally of the jar and underneath thereof, and are secured to the ring 5 at two places. These bands may be arranged as shown in Figure 4, in which 90 case the ends of the bands 12 are continued beyond the ring 5, the continuations forming the tongues 4. They can however be so arranged that the continuations may act as the spring clips or one continuation may 95 form the spring clip and the other continuation the tongue. Again the bands 12 may terminate at the ring 5, the spring clips and tongues being arranged at different places around the ring 5.

In the case of jars having flanged mouths the device can be arranged so that the spring clips, tongues and washer are carried by the lid. In such case, a ring 13 is arranged 100 around the brim of the lid and retained in position by tongues 4 which are bent over the washer 3 for the purpose hereinbefore described. Spring clips 14 also attached to the ring 13 have inwardly projecting fingers 15 which cause the spring clips to be 105 moved outwardly when the lid is being placed in position. These fingers fit against 110

the underside of the flanged mouth 6 of the jar when the washer 3 makes contact with the jar, thus locking the jar and lid together. In the case of jars provided with 5 a groove in place of the flanged mouth, the fingers on the spring clips can be suitably shaped to fit therein.

I claim:

1. Closing means for jars and the lids 10 thereof having complemental seating surfaces, comprising a washer for application to one of said seating surfaces, positive retaining elements in continuous contact with said washer for permanently securing 15 said washer in position, means for releasably locking the lid to the jar, and positioning means for said retaining elements and said lid locking means.

2. Closing means for jars and the lids 20 thereof having complemental seating surfaces comprising a washer for application to one of said seating surfaces, tongues in continuous contact with said washer for permanently retaining said washer in position on a seating surface, means for releasably locking the lid to the body of the jar and positioning means for the tongues 25 and the lid locking means.

3. Closing means for jars and the lids 30 thereof having complemental seating surfaces on the lid and body of the jar, a washer for application to one of said seating surfaces, tongues in continuous contact with said washer for permanently retaining 35 said washer in position on a seating surface, spring clips for releasably locking the lid to the body of the jar and positioning means for the tongues and the spring clips.

4. Closing means for jars and the lids 40 thereof having complemental seating surfaces on the lid and body of the jar, a washer for application to one of said seating surfaces, tongues in continuous contact

with said washer for permanently retaining 45 said washer in position on a seating surface, spring clips which are integral with said tongues and which releasably lock the lid to the body of the jar, and positioning means for the tongues and clips.

5. Closing means for jars and the lids 50 thereof having complemental seating surfaces on the lid and body of the jar, a washer for application to one of said seating surfaces, tongues in continuous contact with said washer for permanently retaining 55 said washer in position on a seating surface, spring clips which are integral with said tongues and which releasably lock the lid to the body of the jar, and an annular member serving to position said tongues and 60 clips.

6. Closing means for jars and the lids thereof having complemental seating surfaces on the lid and body of the jar, a washer for application to one of said seating surfaces, tongues in continuous contact 65 with said washer for permanently retaining said washer in position on a seating surface, spring clips which have outwardly inclined extensions and which releasably lock the 70 lid to the body of the jar, and positioning means for the tongues and clips.

7. Closing means for jars and the lids thereof having complemental seating surfaces on the lid and body of the jar, a washer for application to one of said seating surfaces, tongues in continuous contact 75 with said washer which are bent over the washer so as only to engage the outer border thereof and which retain the washer on one of said seating surfaces, means for releasably locking the lid to the body of the jar, and means for positioning said tongues and locking means.

WALDO EDWARD BRADEN.
